UNITED STATES PATENT OFFICE.

GEORGE L. WALLACE AND WALTER VAN PATTEN STEIGER, OF BRIDGEPORT, CONNECTICUT, ASSIGNEES TO MORRIS W. SEYMOUR, TRUSTEE.

STOVE-RIM-POLISHING MACHINE.

1,042,509.

Specification of Letters Patent.

Patented Oct. 29, 1912.

Application filed March 12, 1910. Serial No. 548,825.

To all whom it may concern:

Be it known that we, GEORGE L. WALLACE and WALTER VAN PATTEN STEIGER, citizens of the United States, and residents of 5 Bridgeport, in the county of Fairfield and State of Connecticut, have invented certain new and useful Improvements in Stove-Rim-Polishing Machines, of which the following is a specification.

10 This invention relates to buffing and polishing machines and particularly to a machine for buffing and polishing stove rims so called or similar work having annular curved surfaces such as circular piece or 15 pieces usually attached to cylinder types of coal oil stoves and used as a guard or foot rest. In practice these stove rims are formed of sheet or cast metal and their faces polished both preparatory to and after 20 plating; some of them are made in the form of complete rings while others represent but a portion of the ring. The peripheral surfaces of said rings are usually oval so that in cross section they represent sub- 25 stantially a quarter circle. We have therefore produced the following described machine for polishing metal pieces of the above class in a quick, efficient and inexpensive way, thereby accomplishing a piece of work 30 which has heretofore been done largely by hand at a much greater cost than can be done by our machine.

Upon the accompanying three sheets of drawings forming a part of this specification 35 similar characters of reference will be found to denote like or corresponding parts throughout the several figures and of which, Figure 1, shows a front view of our improved rim polishing machine in operative 40 position, with stove rim attached. Fig. 2, shows a side view of the machine shown in Fig. 1. Fig. 3, is a sectional plan of lower part of machine taken on line 3—3 of Fig. 1, and Fig. 4, is a further horizontal section through the lower part of the machine and taken on line 4—4 of Fig. 1.

Referring in detail to the characters of reference marked upon the drawings 10 represents a horizontal base that is supported by legs 11—11 secured to its opposite ends. This base is of a special construction and serves to support the several parts of the machine except the counter shafts for operating the same. To the rear 15 of this base is secured an upwardly disposed

bracket 12 that carries the driving connections and spindle for supporting the chuck that holds the rim to be polished. This bracket will be seen at the right of the bed and is adjusted to the right or left by reason 60 of a rack 12' mounted in the rear portion of the base and engaged by an adjusting pinion 13 secured upon a short shaft journaled in the said bracket 12 and designed to adapt the machine to accommodate various sized 65 rims. Referring to this mechanism (see Figs. 1 and 2) 13' represents a driven pulley that is mounted upon a short shaft 14 journaled in bearings 14' secured to the bracket 12 and upon which shaft is mounted 70 a worm 15 that meshes with and drives a gear 15' secured to the rear end of the chuck spindle 16 mounted in a sleeve bearing 16' that is made adjustable longitudinally within the bearings 17 of the bracket 12 to bring 75 the chuck into proper operative relation to the pivotal point 54 of polishing wheel bracket. The means for accomplishing this adjustment comprises a rack 17' formed upon the underside of the sleeve and engaged by a pinion 18 mounted upon an adjusting shaft 18' journaled within the bracket 12 and adapted to be operated by means of a wrench or other suitable tool applied to the squared end of the said shaft 80 18'. A chuck 19 of any suitable character is secured to the forward end of this spindle 85 for the attachment of the stove rim 20.

Upon the rear end portion of the spindle 16 is secured a worm 21 that meshes with 90 and drives a worm gear 22 upon a vertical shaft 23 journaled in suitable bearings secured to the bracket 12, and has secured to its lower end a bevel gear 24 that meshes with a similar bevel gear attached to a cross shaft 25 also journaled in the bracket 12. This cross shaft is further provided with a bevel gear 26 which meshes with gear 26' slidably keyed to shaft 27 95 and housed in bracket 12 to move therewith. This shaft 27 is mounted in the base 10 before referred to and operated by reason of power transmitted from the driving pulley 13 through the worm, gear and shaft connections before referred to.

A saddle 28 is adjustably mounted upon ways 29 of the base and arranged across the front side thereof. This saddle through additional connections serves to carry the buffing or polishing wheel which as designed 110

may be moved to and from the stove rim on the chuck, and likewise be swung around so as to operate upon both the periphery and side portion thereof. The said adjusting mechanism is designed to be operated by foot power and consists of a rocker shaft 30 mounted in hangers 31 and 32 secured to the underside of the base 10. A foot lever 33 is secured to the said shaft in a way to operate the same in one direction while a second foot lever 34 is loosely mounted on the same shaft, and to the hub portion of each of these levers is secured a bevel gear segment 35 which engages a bevel idler gear 36 loosely mounted upon a stud 37 secured to the hanger 31.

From the foregoing construction it will be seen that a downward thrust of the foot lever 34 hung free upon the rocker shaft, will through the segments and idler gear impart an upward movement of the other lever 33 and thus turn the rocker shaft in one direction while a similar downward movement of the other lever 33 will turn the shaft in the opposite direction and again raise the first named lever 34. Upon the other end on this rocker shaft is secured an arm 38 having a cam groove 39 in its outer face that engages a pin 40 secured on the underside of the before mentioned saddle 28 and whereby the said saddle is moved longitudinally upon the ways of the base so as to shift the buffing wheel to and from the work to be operated upon. A swinging bracket 41 is hinged to the said saddle and is provided with mechanism for swinging the same which is operated from the before mentioned longitudinal shaft 27. This bracket carries a polishing wheel spindle 42 that is driven through a separate belt connection from an overhead counter shaft which we will later describe. Bearings 43 and 44 are formed upon the rear side of the saddle 28 and disposed intermediate the top and bottom portion of the bed to carry a short shaft 45 and engage a gear 46 slidably mounted upon the longitudinal shaft 27. Upon the short shaft is mounted a grooved cylinder cam 47 and gear 48 which latter meshes with the before mentioned gear 46 upon the driven shaft 27. Upon the inner side of the gear 46 is formed one member 49 of a clutch that is designed to be engaged with or disengaged from the adjoining clutch member 50 secured to the driven shaft 27 and whereby the gears, cam and connecting parts may be connected and driven by the said shaft. A slide rack 51 fitted in ways on the saddle bears a pin 52 that engages the before mentioned groove of the cam so that the rack is slid backward and forward with the rotation of the cam. The toothed edge of the rack meshes with a segment 53 having an extended arm to which the swinging bracket 41 is secured. The said segment is

secured to a vertically disposed pivot 54 that passes freely through bearings 55 of the saddle, and is engaged at its upper and lower ends by the said swinging brackets and forms a pivot from which the bracket 70 not only swings but toward and from which both the buffing wheel and chuck are adjusted. The top of the swinging bracket 41 is provided with a dovetailed way 56 to receive a correspondingly dovetailed base portion of a standard 57. In the upper end of this standard is journaled the spindle 42 that carries the polishing or buffing wheel 58 upon one end and a belt pulley 59 upon the other end. An arm 60 is secured to the 80 saddle and carries an adjusting nut 61 that engages a screw carried by the standard 57 and whereby the standard and its operative parts may be adjusted upon its bracket. A spring 61' is mounted upon this nut in a 85 way to form a cushion, so to speak, for the buffing wheel and better to overcome any uneven surface of the stove rims when being polished.

From the foregoing it will be seen that 90 the swinging bracket and parts carried thereon are swung in and out with each complete turn of the cam so as to move the buffing or polishing wheel back and forth across the face and side of rotating stove 95 rim mounted upon the chuck.

The buffing or polishing wheel 58 is driven through its spindle and pulley from an overhead counter shaft that is made to move to accommodate the radial swinging 100 movement of the said buffing wheel. This movable device comprises a vertically disposed shaft 62 that is hung from the ceiling directly above the pivot 54 for the swinging arm and upon this shaft is mounted a driven 105 and driving pulley 63 and 64 respectively. Upon this shaft is also hung a bracket 65 to the lower portion of which is secured a pulley 66 that is connected by a cable 67 over suitable guide pulley 68 with a similar 110 grooved pulley 69 secured to the lower end of the pivot 54 and whereby the cable runs back and forth with the movement of the pivot and its swinging bracket in a way to operate the upper grooved pulley 66 and its 115 bracket in unison with the movement of the said swinging bracket whereby maintaining the driving mechanism of the counter-shaft in juxtaposition to the pulley and polishing spindle. The belt 70 for forming this driving connection is carried around the driving pulley 64 then over idlers 71—71 secured to the sides of the bracket 65 and then down around the spindle pulley 59.

In the operation of our machine the rims 125 20 are secured to the chuck 19 whereby they are rotated during the operation of the buffing wheel which is driven at a high rate of speed and moved back and forth across the rim and engaged therewith by an operation 130

of the foot lever 33. This movement of the saddle and its parts likewise connects the clutch members 49 and 50 is a way to operate the cam 47, its rack 51 and swinging arm 5 in a way to guide the polishing wheel back and forth across the face of the rim. When this operation is completed the other foot lever 34 would be operated in a way to shift the slide 28 a swinging gate thereon and its 10 buffing wheel away from the rim. All adjustments of both the chuck and buffing wheel are made toward and from the pivotal pin 54.

Having thus described our invention what 15 we claim and desire to secure by Letters Patent is:—

1. In a polishing machine for annular work, the combination of a driven rotatable work holding chuck adjustable axially of 20 and transversely to its axis of rotation, a power driven resiliently mounted polishing wheel adjustable to and from the work holding chuck and having a swinging motion around the face of the work, said swinging motion being derived directly and positively from the rotation of the work holding chuck, substantially as shown.

2. In a surface polishing machine for annular work, the combination of a driven rotatable work holding chuck, a yieldingly mounted power driven rotatable polishing wheel adjustable to and from the work and controlled to swing over the surface of the work, substantially as shown.

3. In a surface polishing machine for annular work, the combination of a driven rotatable work holding chuck, a driven rotatable polishing wheel resiliently mounted and arranged to swing around an axis coincident with the center of the generating curve of the polished surface, and driving pulleys mounted in a frame swinging on a center coincident with the axis of the polishing wheel substantially as shown.

4. In a polishing machine for annular work, the combination of a driven rotatable work holding chuck, a power driven polishing wheel having a positively controlled swing motion over the work derived positively and directly from the rotation of the work holding chuck, and means for automatically disconnecting the driving mechanism between the work holding chuck and the swinging polishing wheel when the latter is withdrawn from working contact with the work in the chuck.

5. In a polishing machine of the class described, the combination of a chuck for carrying a stove rim and means for rotating the same, a slide with means for moving the same toward and from the chuck, a bracket pivoted to the slide and adapted to be swung circularly therefrom, a polishing wheel mounted upon the bracket with means for operating the same and adapted to be moved

with the bracket to operate circularly across the face of the rim.

6. In a polishing machine of the class described, the combination with a chuck for carrying stove rims and means for rotating 70 the same, of a slide, a swinging bracket pivoted to the slide, a rotatable polishing wheel mounted upon the bracket, means for swinging the bracket upon its pivot to and from the slide to move the wheel across the face 75 of a stove rim.

7. In a polishing machine of the class described, the combination with a chuck for carrying stove rims and means for rotating 80 the same, of a slide, a swinging bracket pivoted to the slide, a standard adjustably mounted upon the bracket, a rotary polishing wheel mounted in the standard, means for swinging the bracket upon its pivot to and from the slide to move the wheel across 85 the face of a stove rim.

8. In a polishing machine of the class described, the combination of a base, a spindle and chuck mounted thereon, a slide also mounted upon the base, means for shifting 90 the slide longitudinally upon the bed, a bracket pivoted to the slide, a cam and slide rack for operating the bracket, a polishing wheel carried by the bracket and adapted to operate to and from and across the periphery of the chuck.

9. In a polishing machine of the class described, the combination of a base, a spindle and chuck mounted thereon, a slide also mounted upon the base, a shaft with connection for rocking the same, a grooved faced cam mounted upon the shaft and engaging a pin of the slide for shifting the same back and forth upon the bed, a bracket pivoted upon the slide, means for swinging the bracket upon its pivot to and from the slide, a polishing wheel mounted upon the bracket and having means for driving the same while being moved with the bracket.

10. The combination of a base, a bracket secured thereon, a spindle and chuck carried by the bracket, a shaft mounted longitudinally in the base, means for driving both the spindle and shaft, a slide mounted upon the base, a cam carried by the slide, connections 110 from the shaft for operating the cam, a bracket pivoted to the slide and having connections to be operated by the cam, a polishing wheel mounted upon the bracket and adapted to move across the periphery of the 115 chuck.

11. In a stove rim polishing and buffing machine the combination with a base, a saddle slidably mounted thereon, a bracket pivoted to the saddle, a buffing wheel mounted upon the bracket, a rotatable chuck also mounted upon the base for carrying a stove rim, means for adjusting both the chuck and buffing wheel toward and from the pivotal point of the bracket.

12. In a polishing and buffing machine, the combination with a rotatable chuck for carrying a stove rim, a buffing wheel mounted to operate circularly across the face of 5 the rim and a spring to retain the buffing wheel in yielding operative contact with the rim when mounted upon the chuck.

13. In a polishing machine the combination of a work holding chuck, a power 10 driven polishing wheel mounted to have a driven swinging motion to coincide approximately with the generating curve of the work, and mechanism to control said swinging movement of the polishing wheel, all 15 substantially as shown.

14. In a polishing machine, an adjustably mounted power driven rotatable work holding chuck, a power driven resiliently mounted rotatable polishing wheel having a 20 power driven movement transverse to the

work, and independent means to control the transverse movement of the polishing wheel, substantially as shown.

15. In a polishing machine, a power 25 driven rotatable work holding chuck, a resiliently mounted rotatable polishing wheel having a power driven movement transverse to the movement of the work, and independent means to control said transverse movement of the polishing wheel, substantially 30 as shown.

Signed at Bridgeport, in the county of Fairfield, and State of Connecticut, this 9th day of March, A. D., 1910.

GEORGE L. WALLACE.
